UNITED STATES PATENT OFFICE.

RALPH R. SHAY, OF PARK RIDGE, ILLINOIS, ASSIGNOR TO CHICAGO APPARATUS COMPANY, OF CHICAGO, ILLINOIS, A CORPORATION OF ILLINOIS.

SPRING CLAMP.

Application filed October 13, 1923. Serial No. 668,272.

To all whom it may concern:

Be it known that I, RALPH R. SHAY, a citizen of the United States, residing at Park Ridge, in the county of Cook and 5 State of Illinois, have invented a certain new and useful Spring Clamp, of which the following is a specification.

This invention relates generally to a spring clamp and more particularly to one 10 which has two relatively resilient arms slideable on a rod or post.

In many places where such a clamp is desired, especially in laboratory apparatus, there has always been a tendency for those 15 clamps heretofore employed to lose the springiness that normally serves to hold them in the clamped position. This frequently compels one to remove the same and to bend it to regain the resiliency at the 20 required relative position of its parts.

It frequently happens that a delicate instrument is held by the clamp and the above operation seriously interferes with its use. Likewise, it often happens that other clamps 25 are above and below, and it is necessary to remove one set of these in order to have access to the weak clamp to bend it into proper form.

The cause of such growing weakness in 30 the clamp has been due to its manipulation in use. The construction of these clamps heretofore has been such as to permit the user to pinch the resilient arms to a greater degree than necessary to release the clamp.

If, after raising or lowering the clamp to 35 the desired point, the user then lets go of the clamp, it and the article supported thereby may drop, with consequent breakage or damage. It is the object of my invention so to construct the clamp that the 40 resilient arms are arrested in the pinching movement at a point where the smoothest operation occurs, thereby preventing a permanent set in the resilient material of the 45 clamp, as well as facilitating its use.

In the drawings Fig. 1 shows one embodiment of my improved clamp in the clamped position. Fig. 2 shows the improved clamp in free sliding position. Fig. 3 shows a 50 plan view of the clamp of Fig. 2 and Fig. 4 shows the clamp in section, fitting tightly on the post.

In the drawings, 5 represents a standard 55 for supporting a laboratory utensil or instrument. A round post is shown since this

permits adjustment in more than one angular relation, but it will be understood that any form of cross-section is contemplated for use with my invention.

In the type of clamp to which my invention applies there are two arms resilient relative to each other, each arm having holes therein adapted to become alined in some deflected position of the two arms. In the form of clamp shown, generally designated as 6, the arms 7 and 8, being of resilient material, are mutually resilient relative to each other.

Both the arms 7 and 8 have holes 9 and 10, respectively, which conform substantially to the size and shape of the rod 5, being freely slideable on the latter in some one position. In the angular positions shown for these arms in Figs. 1 and 4, the post binds in the holes, each in the opposite direction, and thereby the clamping action is produced. In the clamp shown the arms 7 and 8 are branches of a U-shaped member, having resiliency tending to open outwardly. However any other form may be used 80 wherein such a resilient effect is produced. In the use of the clamp 6 it is readily seen that pinching the two members 7 and 8 will aline the holes 9 and 10 to permit easy sliding on the post.

According to my invention I provide stop members adapted to limit the motion of the arms 7 and 8 at the alined position of the holes 9 and 10. In the preferred embodiment of my invention, I continue the arms 90 7 and 8 forming the members 11 and 12 angular thereto and further bending them to form the parts 13 and 14 as finger pieces. In Fig. 2 the parts 13 and 14 are shown in the pinched position, wherein each finger 95 piece is a stop for the other, thereby limiting the motion of the arms 7 and 8 at the freely sliding position wherein the holes 9 and 10 are alined. The pin 15 projecting from the bend of the clamp serves to support a laboratory utensil or instrument.

It will be understood that the shape of the stop portions and the finger pieces may be varied without departing from the scope of the invention defined in the appended 105 claims.

I claim as my invention:

1. A laboratory support having, in combination, a rod and a spring clamp comprising two arms having holes through which 110

the rod extends, said arms normally standing in such position that the walls of the openings bind on said rod, and finger pieces on the free ends of said arms, said finger pieces being offset inwardly toward each other from the free ends of the arms and adapted to be pinched into contact with each other and thus serve to limit approaching movement of the arms into position where 10 they are freely slideable on the rod.

2. A support for laboratory utensils comprising a rod and a spring clamp having

two arms with holes thru which the rod extends, the free ends of the arms having finger pieces offset inwardly toward each other from the free ends of the arms and adapted to stop against each other to prevent excessive bending of the arms, and a pin projecting outwardly from the clamp and adapted to support a laboratory utensil. 15 20

In testimony whereof, I have hereunto affixed my signature.

RALPH R. SHAY.
